UNITED STATES PATENT OFFICE.

WILLIAM BERICIELLI, OF ALBANY, NEW YORK.

SAFETY-RAZOR CLEANER.

Application filed April 28, 1928. Serial No. 273,583.

The present invention relates to attachments for safety razors of the Gillette type and has for its object to provide a combined cleaner for the prongs of the blade guard and 5 shield for preventing the lather from dripping down the handle of the razor. A further object of the invention is to provide an attachment of this character which may be formed either of a permanent nature for use 10 upon the razor or which may be constructed of inexpensive material so that the attachment may be discarded after each use of the razor. A still further object is to provide an attachment of this character of a simple and 15 practical construction, which is neat and attractive in appearance, which will not interfere with the shaving operation, relatively inexpensive to manufacture and otherwise well adapted for the purposes for which the same 20 is intended. Other objects and advantages reside in the special construction, combination and arrangements of the various elements forming the invention as more fully hereinafter described and claimed, reference 25 being had to the accompanying drawings forming part hereof, wherein like numerals refer to like parts throughout the specification and in which

Figure 1 is an end elevational view of the 30 razor showing a pair of the attachments arranged at the opposite cutting edges thereof,

Figure 2 is a side elevational view, and

Figure 3 is a perspective view of the combined cleaner and shield.

Referring now to the drawing in detail, I 35 have shown my invention adapted for use upon a razor of the well known Gillette type indicated at 5 and which is provided with a blade guard 6 and blade retaining head 7 between which the blade 8 is secured. The 40 guard is provided with a series of spaced fingers 9 between which the lather used during the shaving operation collects and presents difficulty in cleaning after the shaving 45 is completed. My invention proposes a cleaner for the guards 6 of the razor which comprises a substantially rigid sheet of light weight thin material such as celluloid, aluminum or the like having one edge indicated at 50 10 inserted between the blade 8 and the edge of the guard and shaped so as to extend over

the edge of the guard with a series of openings 11 formed adjacent the edge through which the fingers 9 of the guard are inserted, the openings being adapted to form a snug fit 55 with said fingers. The material extends inwardly from the edge of the guard toward the handle in an arcuate formation and with its edge 12 opposite from the edge 10 spread outwardly from the handle so as to deflect any 60 dripping from the cutting edge of the razor away from the handle. As shown in Figure 2 of the drawing the cleaner and shield has substantially the same width as the cutting 65 end of the razor. Figure 1 illustrates the manner in which a pair of the attachments 70 may be arranged on the razor although it is to be understood that only a single attachment may be carried thereon, if desired. It will be apparent that when removing the attachment from the razor that the fingers will be wiped free of any accumulation of lather. It is apparent from the foregoing that the 75 invention is susceptible of various modifications and changes without departing from the spirit thereof or the scope of the appended 80 claims, and I accordingly claim as my own all such forms of the invention to which I am entitled.

I claim:

1. A combined cleaner and shield for razors comprising a sheet of substantially rigid material having one edge arranged for attachment to the razor and having openings for receiving the fingers of the blade guard 85 whereby to wipe the fingers free of lather upon removal of the cleaner from the razor.

2. A combined cleaner and shield for razors comprising a sheet of substantially rigid material having one edge arranged for attachment to the razor and having openings for receiving the fingers of the blade guard whereby to wipe the fingers free of lather upon removal of the cleaner from the razor, 90 said attachment having its opposite edge extended outwardly from the handle of the razor whereby to prevent lather dripping from the cutting end of the razor from engaging the handle thereof.

In testimony whereof I affix my signature.

WILLIAM BERICIELLI.
